CAR STRUCTURE

William M. Sheehan, Merion, Pa., assignor to
General Steel Castings Corporation, Granite
City, Ill., a corporation of Delaware

Application February 23, 1932, Serial No. 594,687

12 Claims. (Cl. 105—364)

This invention relates to dumping vehicles and consists in a novel underframe and body construction particularly for mine quarry and other cars for similar service. Reference is here made 5 to companion application Serial No. 616,673, filed June 11, 1932, and illustrating some of the features described and claimed herein.

The main object of the invention is to provide a vehicle of the above type having the maximum 10 capacity and also having sufficient strength and durability to resist the hard usage to which such vehicles are subjected.

Another object is to shape the floor of the vehicle in a manner to facilitate dumping where 15 the floor must be recessed to accommodate various equipment.

A still further object of the invention is to provide a seamless floor shaped to eliminate joints, 20 crevices and substantially square corners where chemical agents could repose and cause corrosive deterioration.

An additional object is to provide integral longitudinal strengthening members in the underframe that will permit quick, unobstructed discharge of the contents of the car and also possess maximum lateral and vertical beam value and be effective self-reinforced columns.

These objects and others are attained by the structures illustrated in the accompanying drawings, in which—

Figure 1 is a half top view of an underframe embodying the invention.

Figure 2 is in part a side elevation and in part 35 a vertical longitudinal section on the center line of Figure 1. Figure 3 is an end view of one-half of the car. Figures 4 and 5 are vertical transverse sections taken on the corresponding section lines of Figure 1. Figure 6 corresponds to Figure 1 but illustrates a modification. Figure 7 40 is a longitudinally vertical section taken on the line 7—7 of Figure 6. Figures 8 and 9 are vertical transverse sections taken on the corresponding section lines of Figure 6. Figure 10 is an end view of the car.

45 In Figures 1 to 5, the invention is illustrated as embodied in a one-piece, preferably cast, underframe and body structure having a floor-forming seamless web 100 including side and end walls 101 and 102, respectively, having a 50 continuous reinforcing rib 103 extending around the upper edges thereof.

This car is particularly adapted for use in connection with rotary dumping machines where the structure should be rigid from end to end 55 and from side to side to withstand stresses applied during the rotation of the dumping machine as well as those encountered during loading and transportation involving the dropping of heavy weights into the car and the transmission of draft 60 and buffing forces.

Extending from end wall to end wall is a corrugation or recess 106 formed in the main web 100 with opposite sides extending upwardly from the flat center and side portions of the web. This corrugation is widened and deepened adjacent 5 the car wheels 148, as indicated at 107. Transverse corrugations 108 extend between corrugations 107 on opposite sides of the car but terminate short of the latter, the end portions of corrugations 108 merging with the flat body of 10 the main web 100. Elements 109 depend from web 100 to receive wheel axles 110.

Extending outwardly from each end wall are horizontal members 125 and 126, the ends of which are interconnected by walls 127. These 15 parts cooperate with each other and the adjacent portion of the end wall to form a housing for a draft and buffing device, one form of which is indicated generally at 128, and is the subject matter of my copending application Serial No. 20 602,925, filed April 4, 1932.

The housing forming elements also constitute an end sill for transmitting the draft and buffing forces to corrugations 106, the ends of which are inclined upwardly to substantially align with the 25 upper member 125. The lower member 126 is aligned with the body of web 100.

Figures 6 to 10 illustrate a car having the major portion of its floor at a lower level than the axles. The floor forming seamless web 130 has two corrugations 131 forming longitudinal beams and these corrugations are provided with relatively short upwardly extending recesses 132 and 133 for receiving respectively the car wheels and the stub axles therefor. One side of each recess 133 30 slopes gradually towards web 130, as indicated at 134, to provide space for the insertion of an axle retaining bolt through the holes 135 in the axle engaging ribs 136. The opposite wall of recess 133 is more nearly vertical but is spaced 40 far enough from ribs 136 to permit the insertion of a nut for said bolt.

At the ends of the car, web 130 curves and inclines upwardly, as indicated at 146, merging with the end sill or end wall 137 at a point 45 spaced above the lower edge thereof. This arrangement forms an angular transverse beam of substantial depth vertically and horizontally for effectively transferring the buffing and draft forces from the central portion of the car to 50 the longitudinal corrugations 131 and to the sides of car 139. A reinforcing flange 138 on the bottom of sill 137 gives the beam a triangular conformation. The wall of longitudinal corrugation 131 arcuately merges with the inclined 55 portion 146 of the bottom web.

One end of the car (Figure 6) has been shown with the corners bevelled to provide clearance between adjacent cars on curved track, while the other end of the car has been shown as hav- 60

ing a substantially right angled corner. It will be understood that both ends of the car may be the same and that the other features described may be utilized irrespective of the corner construction.

5 It will be seen that in one form of the invention a substantial portion of the vehicle floor is located beneath the level of the tops of the wheels and of the draft housing. However, the offsets thereby formed in the floor to accommodate these parts are prevented from obstructing the ready dumping of lading material by the gradual sloping of the faces of such offsets in the direction opposite the open end of the body, and maximum 10 capacity is assured by the sharp inclination of the surfaces of such offsets facing the dumping door and free expulsion of the lading is hastened by the arcuate formation of the corners of the floor web.

15 20 The invention is illustrated as embodied in a car which is intended to be rolled onto a tiltable or rotary platform in dumping, but the essential features thereof might be readily embodied in vehicles intended for other use and, accordingly, 25 various details of the structures shown may be modified to most advantageously accommodate the type of service for which the vehicle is intended. The exclusive use of all such modifications as come within the scope of the appended 30 claims is contemplated.

What is claimed is:

35 1. In a car underframe, an end sill, a floor-forming seamless web having an upwardly recessed wheel receiving portion of restricted length and a reinforcing corrugation of U-shape connecting said sill and said recessed portion.

2. In a car of the class described, a floor-forming seamless web, vertically spaced horizontal members constituting a buff and draft receiving 40 structure, end elements connecting said web and members, a corrugation in said web extending longitudinally of the car, the body portion of said web merging with the lower of said members and the upper portion of said corrugation merging with the upper of said members.

45 3. In a car of the class described, wheels and stub axles, a floor-forming seamless web including a main body portion extending substantially throughout the length of the car at a lower level than said axles, there being a longitudinal corrugation in said web substantially throughout the length of the car forming a longitudinal beam, said corrugation and adjacent portions of said web having upwardly extending recesses for 50 receiving said wheels and axles.

4. In a car of the class described, an upright end sill web, a floor-forming seamless web constituting the car underframe and extending substantially throughout the length of the car with 55 its end portion inclined upwardly and merging with said sill web at points spaced above the bottom of the latter and including upright elements at the sides of the car for better resisting longitudinal forces, said sill and the adjacent portion of said floor web cooperating to form an angular transverse beam of substantial vertical and horizontal depth for transferring buffing and draft forces from the central portion of the car to said side elements.

70 5. A structure as specified in claim 4 in which upwardly extending longitudinal corrugations are

formed in said web spaced from the center line of the car with the walls of said corrugations merging with said inclined portions of said web.

6. A structure as specified in claim 4 characterized by the presence of an inwardly extending 5 flange on the lower portion of said end sill co-operating with the body of said sill and with said inclined portion of said web to provide said end beam with a triangular conformation.

7. In a car of the class described, an end sill, 10 a floor having an upwardly recessed wheel-receiving portion of restricted length and spaced from said end sill and also having an inverted U-shaped part forming a longitudinal reinforcing element extending from said wheel receiving 15 portion to said end sill.

8. In a railway car, wheels, a web forming the car floor and underframe and extending substantially from side to side of the car and having upwardly concaved recesses extending substantially throughout the length of the car to reinforce said web in transmitting longitudinal forces, portions of said recesses being constructed and arranged to receive the upper parts of said wheels.

9. In a railway car, a floor forming web extending throughout the width of the car and including substantially continuous corrugations intermediate its sides adapted to receive the upper portions of car wheels and extending substantially from end to end of the car to substantially 30 reinforce said web in resisting draft and buffing forces.

10. In a car of the class described, an axle and wheels, a floor forming seamless web including a main body portion located at a lower level than 35 said axle, said web being recessed upwardly to receive said axle, the sides of the axle receiving recess being inclined from the vertical, and an axle engaging element depending from the upper portion of the axle receiving recess, a wall 40 of the recess at one side of said element being offset transversely of the axle to provide for the insertion of an axle retaining bolt horizontally through said element.

11. In a car of the class described, an upright 45 end sill web, draft elements thereon, a floor-forming seamless web constituting the car underframe and extending substantially throughout the length of the car with an end portion inclined upward and merging with said sill web above 50 the bottom of the latter, and including upright elements at the sides of the car for better resisting longitudinal forces, and elements cooperating with said sill web and the inclined portion of said floor web to form an angular transverse 55 beam of substantial vertical and horizontal depth for transferring longitudinal forces from said draft elements to said side elements.

12. In a vehicle of the class described, a floor web having an upwardly recessed portion forming 60 a wheel receiving housing, an end sill extending upwardly from said floor and spaced from said recess, and a longitudinally extending inverted U-like corrugation in said floor between said end sill and said recess, said corrugation being narrower than said recess, and at least one side of said corrugation being inclined from the vertical to facilitate the discharge of lading when the vehicle is dumped.

WILLIAM M. SHEEHAN. 70
